CURTAINLESS SAND BLAST NOZZLE CONTROL

Application filed May 28, 1930. Serial No. 456,318.

This invention relates to improvements in sand blast nozzle control.

It has for its object to provide means for adjustably mounting a sand blast nozzle in such a way that it may be always held at right angles to the work and moved instantaneously either longitudinally or vertically, and all over the face of the work.

It is also an object of this invention to provide a counterbalance means for holding the sand blast nozzle in certain adjusted positions.

It is a further object of this invention to provide in connection with a sand blast room, having an opening therein, means across the opening to protect the eyes of the operator from the backward flying sand and to prevent the backward flying of the sand beyond the confines of the room.

20 It is particularly the object of this invention to provide in connection with a sand blast room, means for pivotally supporting a pair of guides in which are located sliding tubes, one of which is on the outside for 25 operating purposes, and the other of which extends into the room and has located thereon at suitable points a sand blast nozzle and light means. In connection with the interior sliding tube there is provided means for holding the tubes in adjusted position. There is also provided in connection with this inner tube, means for supplying electric current to the lighting means located thereon.

These and other advantages will appear 35 from the description taken in connection with the drawings.

Referring to the drawings:

Figure 1 is a front elevation of a sand blast room showing the opening therein 40 closed by a wire screen. This figure also shows the outside sliding tube in one position in full lines, and in two other positions in dotted lines.

Figure 2 is a vertical section taken on the 45 line 2-2 of Figure 1.

The numeral 1 is used to designate the sand room, which may be of any suitable and convenient shape and size. In the present instance this room is rectangular in shape, having 50 four side walls and a top. In the front

wall is an opening across which there is stretched a wire screen 2. In the top there is a slot, the purpose of which will be later described.

Located on top of the room between the slot 55 and the front wall is a shaft or axle 3 supported adjacent each end by a bearing 4. On each end of this shaft or axle is a steel flange 5, solidly attached thereto. To each of these flanges is also solidly attached a tubular steel 60 guide member 6. These guide members and the shaft freely oscillate in the bearings 4. In each end of each guide are roller bearings 7 for the purpose of permitting ready longitudinal adjustment of sliding tubes 8 and 9, 65 located in these guides. While both of these slide members are shown as tubular, at least the outer one 8 need not be tubular. The upper ends of these slide members are united by a cross member 10. The member 10 is 70 united to the slide member 8 by means of an elbow joint 11, which is united to the slide member 9 by means of a T joint 12.

On the lower end of the slide member 8 is a handle 13 which is for the purpose of 75 raising the slide members and oscillating them on the bearings 4. On the lower end of the inner slide member 9 is a nozzle clamp 14 for the purpose of clamping in position a nozzle 15. Located on the same slide member 9, above the nozzle clamp, is a bracket 16. To this bracket is attached one end of a cord 17 which passes upward and over two pulleys 18 located on the top of the room. This cord passes from the second pulley down 80 through a hole within the top of the room and supports within the room a counterweight 19. While this counterweight in the present instance is shown within the room it may be properly supported on the outside 85 thereof.

The steel guide member 6 on the inner end of the shaft or axle 3 oscillates within the slot in the top of the room. This slot is sufficiently large to permit ample oscillation of the nozzle for operating purposes. Where the cord 17 passes upward and over the first roller 18 there is also provided a hole or opening in the top of the room for the passage of this cord therethrough. 90 95 100

On the slide tube 9, just above the nozzle bracket, is a light bulb 20 which has associated therewith a reflector 21. For the purpose of supplying electric current to this bulb there extends through the upper end of this slide tube wires 22. Extending from the nozzle is a sand hose 23. This hose passes outside of the sand room at some particular and suitable point. In the present instance it is shown as passing out of the room through the top. While it is not shown, the room has suitable openings therein for the entrance of the work. In the present instance there is shown in the room a truck 24 having thereon the work 25. After the work has been located within the room the opening through which it is admitted may be closed.

The purpose of the screen 2 is to permit the operator to inspect the work and see how it is being carried on, and to properly manipulate the parts without subjecting his eyes to the damaging influence of the backward flying sand. The wire netting is sufficient to prevent the sand flying back outside of the room, and is sufficiently large to permit an inspection and view of the work as it is going on.

The nozzle is manipulated by means of the handle 13. By raising the handle both of the slide tubes move upward and carry with them the nozzle. At the same time these tubes may be caused to oscillate or swing about the pivots 4 so that the nozzle may be adjusted to any point of the work. In order to facilitate the movement up and down of the slide tubes the counterweight 19 is provided. This counterweight is of substantially the same weight as the moving parts of the sand blasting structure. In dotted line in Figure 2 the sand blast nozzle and its operating parts are shown in raised position, with the nozzle above the work as shown in this figure. The nozzle may be adjusted to any desired position up and down or transverse the room. The purpose of the light within the room is to enable the operator to see exactly how the blasting is operating and what effect the sand blast is having upon the work.

We desire to comprehend within our invention such modifications as may be clearly embraced within our claims and the scope of our invention.

Having thus fully described our invention, what we claim is new and desire to secure by Letters Patent, is:

1. In a sand blast control, an oscillatory shaft, a guide on each end of said shaft, a slide in each guide, means connecting one end of one slide to one end of the other slide, a handle on the other end of one slide, and a sand blast nozzle on the other end of the other slide.

2. In a sand blast control, an oscillatory shaft, a guide on each end of said shaft, a slide in each guide, means connecting one end

of one slide to one end of the other slide, a handle on the other end of one slide, and a sand blast nozzle and a light means on the other end of the other slide.

3. In a sand blast control, an oscillatory shaft, a guide on each end of said shaft, a substantially vertically movable slide in each guide, means connecting the upper ends of the slides, a handle on the lower end of one slide to raise and lower and oscillate the slides, and a sand blast nozzle and a light means on the lower end of the other slide.

4. In a sand blast control, an oscillatory shaft, a guide on each end of said shaft, a substantially vertically movable slide in each guide, means connecting the upper ends of the slides, means to oscillate the slides and move them vertically, a sand blast nozzle and a light means on one of said slides, and a counterbalance means connected to one of said slides.

5. In a sand blast control, an oscillatory shaft, a guide on said shaft, a tubular slide in said guide, means to oscillate said slide and move it up and down in the guide, a sand blast nozzle and a light means at one end of the slide, and an electric conductor means extending from the light means through the slide.

6. In a sand blast control, an oscillatory shaft, a guide on said shaft, a tubular slide in said guide, means to oscillate said slide and move it up and down in the guide, a sand blast nozzle and a light means on said slide, an electric conductor extending from the light means through the slide, and means to counterbalance the slide.

7. In a sand blast control, an oscillatory guide, a tubular slide in said guide, means to oscillate said slide and move it in the guide, a sand blast nozzle and a light means on said slide, an electric conductor extending from the light means through the slide, and a sand hose connected to said nozzle.

8. In a sand blast control, a sand room having a slot in the top thereof and an opening in one side, an oscillatory guide on the top of said room extending through said slot, a tubular slide in said guide, means to oscillate the slide and move it in the guide, a sand blast nozzle and a light means on the slide opposite the opening, a wire screen across the opening to prevent sand flying back, and an electric conductor extending from the light means through the slide.

9. In a sand blast control, a sand room having a slot in the top thereof and an opening in one side, an oscillatory shaft on said room, a guide on each end of said shaft, a slide in each guide, one without the room and the other extending through the slot into the room, means to oscillate the slides and move them in the guides, a sand nozzle on the slide within the room adjacent the open-

ing, and a wire screen across the opening to prevent sand flying back.

10. In a sand blast control, a sand room having a slot in the top thereof and an opening in one side, a shaft pivotally supported on said room, a guide on each end of said shaft, a slide in each guide, one without the room and the other extending through the slot into the room, means on the outer slide to oscillate the slides and move them in the guides, a sand nozzle on the slide within the room adjacent the opening, and a wire screen across the opening to prevent sand flying back.

15. 11. In a sand blast control, a sand room having a slot in the top thereof and an opening in one side, a shaft pivotally supported on said room, a guide on each end of said shaft, a slide in each guide, one without the room and the other a tubular one extending through the slot into the room, means on the outer slide to oscillate the slides and move them in the guides, a sand nozzle and a light means on the tubular slide adjacent the opening, and a wire screen across the opening to prevent sand flying back.

20 12. In a sand blast control, a sand room having a slot in the top thereof and an opening in one side, a shaft pivotally supported on said room, a guide on each end of the shaft, a slide in each guide, one without the room and the other a tubular one extending through the slot into the room, means to connect the upper ends of said slides, a handle 25 on the outer slide by which the slides may be moved through the guides and oscillated, a sand nozzle and light means on the lower end of the tubular slide adjacent the opening, electric conductors extending through the 30 tubular slide to the light means, a sand tube connected to the sand nozzle, and a wire screen across the opening.

35 13. In a sand blast control, a sand room having a slot in the top thereof and an opening in one side, a shaft pivotally supported on said room, a guide on each end of the shaft, a slide in each guide, one without the room and the other a tubular one extending through the slot into the room, means to connect the upper ends of said slides, a handle 40 on the outer slide by which the slides may be moved through the guides and oscillated, a sand nozzle and light means on the lower end of the tubular slide adjacent the opening, electric conductors extending through the 45 tubular slide to the light means, a sand tube connected to the sand nozzle, a wire screen across the opening, and a counterweight connected to one of the slides.

50 60 14. In testimony whereof we affix our signatures.
